UNITED STATES PATENT OFFICE.

SOLOMON F. WEITMAN, OF LIVE OAK, FLORIDA.

BALING-PRESS.

1,351,360.

Specification of Letters Patent. Patented Aug. 31, 1920.

Application filed November 13, 1917, Serial No. 201,787. Renewed January 29, 1920. Serial No. 354,886.

To all whom it may concern:

Be it known that I, SOLOMON F. WEITMAN, a citizen of the United States, residing at Live Oak, in the county of Suwanee, State of Florida, have invented a new and useful Baling-Press; and I do hereby declare the following to be a full, clear, and exact description of the invention, such as will enable others skilled in the art to which it appertains to make and use the same.

This invention relates to a baling press, and particularly to an improved plunger operating mechanism for the press.

One of the objects of the invention is to provide a simple, improved and practical structure of operating means for the plunger of a baling press, and one which may be manufactured for a small cost and sold at a reasonable profit.

A further object of the invention is to provide a baling chamber, a plunger therein, a U-shaped lever mounted upon the sides of the baling chamber and having link connections with said plunger whereby as the lever is tilted forwardly, the plunger is reciprocated forwardly in the chamber.

A further object of the invention is to provide elongated slots in the side walls of the chamber of the press in which the ends 30 of the arms of the U-shaped lever move, so that the lever may be moved forwardly and the plunger correspondingly moved, to discharge the bale from the forward end of the chamber, after it has been tied.

In practical fields the details of construction may necessitate alterations falling within the scope of what is claimed.

The invention comprises further features and combination of parts as hereinafter set forth shown in the drawings and claimed.

In the drawings:—

Figure 1 is a view in side elevation of the improved baling press constructed in accordance with the invention.

Fig. 2 is a plan view.

Fig. 3 is a longitudinal sectional view on line 3—3 of Fig. 2.

Fig. 4 is a sectional view on line 4—4 of Fig. 3.

Fig. 5 is a detail perspective view of the curved rack for locking the pivoted lever which moves the plunger.

Referring more especially to the drawings, 1 designates a casing of a baling press provided with a baling chamber 2 and a hopper 3, through which the hay is passed

into the chamber 2. Mounted in a guide opening 4 at the rear end of the casing 1 is a plunger rod 5, and threaded on this rod is a cross bar 6, there being nuts 7 and 8 also threaded upon the plunger rod to prevent displacement of the bar 6 with respect to the plunger rod. The forward portion of the plunger rod has a shoulder 9 and a threaded extension 10 beyond the shoulder. This extension 10 enters an opening in the center of the baling plunger 11, and a nut 12 is threaded on the extension 10 to hold the baling plunger in place. The ends of the bar 6 are mounted and guided in opposite guide slots 13 of the sides of the baling chamber, and the ends of said bar have secured therein bolts 14, by means of nuts 15. Said bolts are provided with eyes 16, in which the eyes 17 of the opposite links 18 are connected. The lower opposite rails 19 of the casing of the baling press are provided with elongated slots 21, the rear ends of which are provided with offset portions 22. A U-shaped lever 23 is provided, and the lower ends of the arms of said lever have pivot pins 24 which are, when it is desired to remove the completed bale from the end of the press raised out of engagement with the notches 22 and into the slots 21 so as to allow the plunger 11 to move forwardly when it is desired to remove the completed bale from the press. The links 18 are in turn pivoted at 25 to the side arms of the U-shaped lever. In baling the hay, it is passed through the hopper 3 into the chamber 2, and by moving the U-shaped lever on its pivot, the pivot pins 24 having been seated in the offset notches at the rear ends of the slots 21, the plunger may be moved alternately in the chamber 2, to pack and bale the hay into the chamber. Mounted in bearings 26 at the lower portion of the forward ends of the sides of the bale press casing is a rod 27 on which the forward end piece and the bottom piece 28 and 29 are hingedly mounted. After the hay has been baled, the bottom piece may be opened and the bale removed, that is after it has been tied. In order that the bottom piece 29 can be opened the baling press is designed to be mounted upon suitable legs or supports (not shown), so that the bottom piece may be swung downwardly and the bale removed. The rear end of the bottom piece has secured to it as shown at 30 an angle plate 31 the upright portion of

which is designed to receive a bolt 32 to fasten the plate to the casing of the press. Pivoted at 33 on the rear face of the end piece 28 on a suitable lug 34 is a curved toothed rack 35, which is under tension of the spring 36. The arch portion of the U-shaped lever has a rib 37, which is designed to engage any one of the teeth of the toothed rack, to hold the lever tilted downwardly on its pivots as shown in Fig. 1. By throwing the lever upwardly and the rack downwardly and moving or opening the end piece 28, the bale of hay may be forced out of the forward end of the baling press. This may be accomplished by raising the pivots 24 out of the offset portions 22 of the slots 21 and moving the lever bodily forwardly, the pivot pins moving in the slots, while the plunger will force 20 the bale of hay through the chamber and out of its forward end.

The invention having been set forth what is claimed as new and useful is:—

1. In a hay baling machine, a frame having a baling chamber provided with guides, a plunger mounted in said chamber, means mounted in said guides and connected to the plunger, whereby the plunger may be guided in its movements, and a U-shaped lever having its arms pivoted to the sides of the baling frame and having link connections with said means for moving the plunger, the forward end of the baling chamber having on its outer face a pivoted spring tensioned rack, to be engaged by the arch of the U-shaped lever to hold the same tilted forwardly and downwardly as the plunger moves forwardly.

2. In a hay baling machine, a frame having a baling chamber provided with guides, a plunger mounted in said chamber, means mounted in said guides and connected to the plunger, whereby the plunger may be guided in its movements, and a U-shaped

lever having its arms pivoted to the sides of 45 the baling frame and having link connections with said means for moving the plunger, said baling chamber having a forward hinged end, the lower portions of the side walls of the chamber having elongated 50 slots provided with offset portions at their rear ends to receive the pivot pins, whereby the lever may be pulled forwardly by removing the pivot pins from the offset portions and causing them to move longitudinally in the slots.

3. In a hay baling machine, a frame having a baling chamber provided with guides, a plunger mounted in said chamber, means mounted in said guides and connected to the 60 plunger, whereby the plunger may be guided in its movements, and a U-shaped lever having its arms pivoted to the sides of the baling frame and having link connections with said means for moving the plunger, said baling chamber having a forward hinged end, the lower portions of the side walls of the chamber having elongated 65 slots provided with offset portions at their rear ends to receive the pivot pins, whereby the lever may be pulled forwardly by removing the pivot pins from the offset portions and causing them to move longitudinally in the slots, the forward face of the forward end having a pivoted spring tensioned rack to be engaged by the arch of the U-shaped lever to hold the same tilted 70 forwardly and downwardly when the forward end piece is closed, to hold the plunger in its forward position.

In testimony whereof I have signed my name to this specification in the presence of two subscribing witnesses.

SOLOMON F. WEITMAN.
